WAVE SIGNALING SYSTEM

John F. Farrington, Flushing, N. Y., assignor to
Hazeltine Corporation, a corporation of Delaware

Application May 7, 1935, Serial No. 20,197

42 Claims. (Cl. 250—20)

This invention relates to selective wave signaling systems and more particularly to tunable radio broadcast receiving systems adjustable in selectivity for reproducing speech or music from 5 modulated carrier wave signals with optimum fidelity consistent with the avoidance of interference from static or from stations operating on adjacent carrier channels.

The invention provides a tuned modulated carrier wave receiving system the selective properties of which are adjustable both in frequency for the purpose of optional station selection, and in the width and allocation relative to the carrier frequency of the band passed for controlling 15 the character of reception. The manipulation of the system is such as to select and pass a relatively narrow frequency band in the process of station selection in order to sharpen the tuning to the carrier frequency. Thereafter and without disturbing the tuning of the system to the reception frequency carrier, the resonance band width may be expanded symmetrically about the carrier frequency of a modulated carrier wave in order to select both of its sidebands equally, there- 20 25 by to secure double sideband reception the fidelity of reproduction of which is improved in proportion to the expansion of the resonance band. Alternatively the resonance band may be expanded unsymmetrically from the sharp tuning adjustment to select more of one sideband than of the other thereby to provide either upper or lower sideband reception wherein fidelity of reproduction again increases in proportion to the degree of expansion.

30 A broad feature of the invention, therefore, resides in expanding band selectors of the symmetrical and unsymmetrical type in which tuned circuits are reactively coupled to form the band selector and adjustable reactance means are provided for symmetrical and unsymmetrical expansion.

Radio broadcast signals are ordinarily transmitted on a carrier wave having two sidebands of modulation, which are about six kilocycles in 45 width on either side of the carrier. Under the present radio broadcast operating conditions, the carrier frequencies for the various broadcasting stations are located at frequency spacings of ten kilocycles. In many instances the sideband frequencies of a station operating on one carrier channel overlap those of an adjacent channel or else encroach closely upon them.

In either case it is difficult, when tuning a radio broadcast receiver to a desired station, to eliminate entirely interference from stations operat-

ing on adjacent channels, particularly when the interfering signals from said stations are intercepted at the receiving antenna with a strength comparable to or exceeding that of the desired station. In addition to interfering signals, static 5 and other so-called background noise may prevent undisturbed, i. e., quiet, reception of the station selected.

Quiet operation in the presence of interference may be secured by increasing the selectivity, that 10 is, by contracting the resonance band, to prevent appreciable reproduction of the interfering signals and noise. Increasing the selectivity or narrowing the selected band, however, tends to impair the fidelity of signal reproduction, since 15 the sideband frequencies corresponding to the higher audio frequencies of modulation are suppressed. It is desirable therefore that the selected band width be made narrow only when 20 excessive interference or noise is present, but in its absence, the band width should be adjusted freely to admit and pass all sideband frequencies required for faithful reproduction of the received signals.

Either of two methods may be employed for 25 altering the selectivity to the ends stated. One method comprises expanding or contracting the resonance band symmetrically with reference to the carrier frequency thereby to transmit the carrier and a selected portion of both sidebands. 30 The other method is that of expanding the resonance band unsymmetrically to one side or the other of the carrier to receive and reproduce signals constituting a desired fraction of but one sideband and the carrier. The preferred method 35 of selection depends on conditions of reception in a particular instance.

Symmetrical expansion is generally preferable 40 for ease and accuracy in tuning to a selected station, because fidelity is not a critical function of tuning. Also when the signal is subject to like interference or noise on both sidebands, symmetrical expansion produces less interference relative to the signal. On the other hand, when 45 the desired signal is subject to major interference only on one sideband of the selected station such as that nearest in frequency to the carrier of an interfering station, the unsymmetrical or single sideband expansion is of considerable advantage 50 in that selection of the sideband remote from the interfering station greatly reduces its interfering effect.

As applied to a superheterodyne receiver in accordance with a preferred embodiment, the invention provides a plurality of tunable reception 55

frequency circuits and a plurality of tuned intermediate-frequency band selectors. Each tuned intermediate-frequency selector is formed of a plurality of resonant circuits preferably coupled 5 adjustably both inductively and capacitively. Tuning to a desired station is effected by variation of the reception frequency selectors. Expansion of the resonance band for upper, lower, or double sideband reception in a degree desired. 10 is accomplished in the tuned intermediate-frequency selectors, preferably by adjustment of the inductive and capacitive couplings. Thus for symmetrical double sideband expansion the inductive coupling alone may be varied; for un 15 symmetrical or single sideband expansion the capacitive couplings alone may be varied; while suitable variation of both couplings as explained below serves to sharpen the tuning to the intermediate frequency.

20 A feature of the invention resides in the novel mechanical construction disclosed for adjusting the selective properties of the receiver as desired. The essence of the construction resides in the use of a control mechanism operable in two degrees of freedom, as for example a shaft capable 25 of rotation and axial displacement. Adjustment in one degree of freedom, is reserved for double sideband expansion, as for example, by utilizing axial displacement of the control shaft to vary 30 only the inductive couplings in the tuned selectors. Adjustment of the control mechanism in a second degree of freedom may be utilized for single sideband expansion, as by rotation of the shaft to vary only the capacitive couplings in the 35 tuned selectors.

40 The control mechanism may be so arranged that adjustment thereof to a certain limiting position or to a particular setting common to both degrees of freedom, so relates the mentioned inductive and capacitive couplings as to sharpen the tuning of the tuned selectors to the intermediate frequency preparatory to adjusting the 45 reception frequency selectors for station selection. The mechanical construction is such, in accordance with a further feature of the invention, that only for this particular setting of the control mechanism can the reception frequency 50 selectors be manipulated for tuning.

In the drawings:

55 Fig. 1 is a circuit diagram of a selector connected in accordance with the present invention as employed to couple successive amplifier tubes in the intermediate-frequency portion of a superheterodyne receiver.

60 Figs. 2 and 3 are performance graphs illustrating the selectivity adjustments of which the system is capable. Fig. 2 shows the selectivity variation for single sideband reception, and Fig. 3 that for double sideband reception. Fig. 4 is a simplified showing of the Fig. 1 selector and Fig. 5 is an analogous simplified showing of an alternative circuit embodying the same general principles of operation. Fig. 6 is a circuit diagram, similar to Fig. 1, of the modified form 65 of coupling system shown in Fig. 5. Figs. 7 and 8 are selectivity performance graphs for the Fig. 6 coupling system.

70 Fig. 9 is a composite circuit diagram and mechanical assembly illustrative of the manner in which the mentioned tuning and selectivity adjustments are effected in accordance with one embodiment of the invention. Fig. 10 shows in plan view a component of the mechanical assembly as sectioned along 9-9 of Fig. 9; while 75 Fig. 11 is a section along 11-11 of Fig. 9.

Figs. 12 to 17, inclusive, illustrate the mechanical features of an alternative embodiment of the invention. Fig. 12 is a side elevation of the assembled apparatus. Figs. 13 to 15, inclusive, are sections taken along lines 13-13, 14-14 and 5 15-15, respectively, of Fig. 12. Fig. 16 is a perspective view of a component of the Figs. 12 and 13 assembly. Fig. 17 is an elevation of the control panel illustrating the arrangement of the tuning and selectivity controls. 10

15 Referring to Fig. 1, a tuned band selector T couples the output of a vacuum tube 1 to the input of a succeeding vacuum tube 2. The selector comprises a pair of similar, singly resonant circuits 3 and 4 each containing a coil L tuned by a shunt condenser C to a selected frequency. Coil L of the secondary circuit 4 is axially adjustable with respect to coil L of the primary circuit 3 (as indicated by the double pointed arrow) for the purpose of varying the shunt inductive coupling M between the circuits. An adjustable condenser E is connected between the upper terminals of the condensers C in circuits 3 and 4 to provide a variable series capacitive coupling between these circuits. 20

25 Signals are selectively relayed from tube 1 through the selector T to tube 2 by connection of primary circuit 3 between the anode 5 of tube 1 and ground 6 through the plate supply battery 7. To complete the output circuit of tube 1, its cathode 8 is grounded through a grid biasing impedance 9. Secondary circuit 4 is connected between the signal control grid 10 of tube 2 and ground. The grid circuit of tube 2 is completed by connecting its cathode 11 to ground 30 through a grid biasing impedance 12.

35 As a circuit refinement, selector T may be terminated to ground in an adjustable resistance P, and switching means 13 and 14 may be arranged to shunt condenser E with a resistance R, in series with a blocking condenser F, to control the selectivity characteristics of the system in a manner explained below.

40 Coil L of circuit 3 is so poled with respect to coil L of circuit 4 that the inductive coupling M 45 opposes the capacitive coupling E. When the capacitive coupling due to E is adjusted substantially to annul the inductive coupling M at a selected frequency, the effective coupling between circuits 3 and 4 will be so small as to 50 provide a single humped highly selective resonance characteristic for selector T such as is obtained with less than optimum coupling. Although the resultant coupling is low for these 55 adjustments it is not zero owing to a small resistance component probably in the mutual inductance branch. Curve a of Fig. 2 graphically illustrates this condition, optimum response being obtained at a desired frequency f which in this case is 175 kilocycles. 60

65 If, starting from this condition, the capacitance of condenser E is decreased, the coupling between circuits 3 and 4 will increase due to the increasing preponderance of the inductive over the capacitive coupling from the condition of balance and the resonance band width of the selector will increase, the center of the response curve shifting continuously toward the higher frequencies as the selectivity decreases, as is depicted by curves b and c. If on the other hand starting 70 from the minimum effective coupling of curve a the capacity of condenser E is increased, the capacitive coupling will increasingly predominate over the fixed inductive coupling to expand the resonance band and shift its center toward the 75

lower frequencies as shown by curves *a* to *e* to *g*. It will be observed that this shifting of the center of the resonance band is accompanied by no diminution, but on the contrary by an increase, 5 in the response at frequency *f* as compared to that at the point of minimum coupling, curve *a*.

The character of selectivity variation effected by adjustment only of the capacitive coupling *E* is ideal for single sideband reception because 10 band width expansion is achieved by maintaining one limit of cut-off substantially fixed to include the carrier frequency, the other limit being variable to include a desired portion of the upper or lower sideband. The limits of adjustment 15 of condenser *E* are such as to include the entire sideband as illustrated by curves *c* and *g*. To this end the maximum capacitance of the condenser *E* is of such a magnitude that the coupling provided thereby is of the order of twice the 20 normal inductive coupling *M*. If, as these limiting adjustments are approached, peaks in the resonance curve become prominent enough to introduce signal distortion, they may be flattened to provide substantial uniformity of response 25 within the transmitted band by terminating the coupling system in resistance, such as *P*, adjusted to a proper magnitude. In general it is sufficient to terminate the output of the selector in a resistance *P*, although a second resistance 30 may be similarly connected across its input.

If for the condition of minimum coupling the response, curve *a*, is too low at the frequency *f*, it may be improved by shunting condenser *E* by a suitably chosen high resistor *R*. The resistor should, however, be disconnected, as by 35 opening switches *13* and *14*, for all coupling adjustments providing expanded selection.

It will be noted that the unsymmetrical expansion for single sideband selection is procured 40 by alteration of the mean frequency of the selector circuits *3* and *4* by changing the self reactance of these circuits by adjusting the condenser *E*, which at the same time varies the coupling reactance between them.

In order to expand the resonance band symmetrically with respect to the carrier frequency *f* to secure double sideband reception, the capacitive coupling *E* is maintained fixed at the value corresponding to curve *a*, and the inductive coupling 45 *M* increased, for example, by moving coil *L* of secondary circuit *4* toward coil *L* of the primary circuit *3*. Fig. 3 illustrates the effect on selectivity of such expansion. Curve *h* is for a partial expansion and curve *i* for an expansion sufficient 50 to include the carrier frequency and all of the two sidebands. The rather prominent resonant peaks of curve *i* may be flattened by adjustment of resistance *P* to provide the substantially uniform response of curve *j* within the transmitted 55 range.

The selector *T* may be adjusted initially for single or double sideband selection at frequency *f* by disconnecting condenser *E* and tuning circuits *3* and *4* to a frequency higher than *f* and 60 such that, with the mutual inductance *M* adjusted to provide a resonance band equal in width to both signal sidebands, the lower resonance peak will be allocated at frequency *f* as shown by curve *k* of Fig. 2.

The circuit of selector *T*, Fig. 1, is basically 65 that of Fig. 4, wherein resonant circuits *3* and *4* are composed of condensers *C* shunted by coils of inductance *L* mutually coupled inductively to provide series arms of inductance *L*—*M* and a 70 shunt arm of inductance *M*. The capacitive cou-

pling *E* is bridged in shunt across the series arms *L*—*M*.

From the above, it will be seen that, for symmetrical expansion, the mutual reactance between the two tuned circuits is adjusted without affecting the self-reactance or tuning of either circuit. For unsymmetrical expansion, on the other hand, both the mutual reactance and the self-reactance, or tuning, of the two tuned circuits are simultaneously adjusted. In this latter case, the circuits may conveniently have a fixed mutual reactance of a given type and an auxiliary mutual reactance of the opposite type or phase and variable between appropriate limits greater and less than the fixed mutual reactance, the former 10 serving to vary also the self-reactance, or tuning, of the circuits. 15

Fig. 5 is a modified circuit accomplishing the same general results as those of Figs. 1 and 4. The change to the circuit of Fig. 5 consists merely 20 in connecting the condenser *E* in series with the mutual inductance *M* rather than across the series arms *L*—*M* as in Fig. 4. The sizes of condenser *E* in the two types of selectors are generally quite different, however. 25

The selector of Fig. 5 is employed as an inter-tube coupling as shown in Fig. 6. Coils *L*, relatively adjustable axially for varying the mutual inductance *M*, are connected in series between the plate *15* of tube *16* and the signal control grid *17* 30 of tube *18*. From the point between coils *L* the coupling condenser *E* is connected to ground. The resonant circuits *19* and *20* are formed by connecting condensers *C* to ground from the plate 35 and grid leads, respectively, of tubes *16* and *18*. 35

Plate current is supplied to tube *16* from grounded battery *21* through a high-frequency choke coil *22* and coil *L* of resonant circuit *19*, the cathode *23* of tube *16* being grounded through the biasing impedance *24* to complete the circuit. 40 In order to isolate battery *21* from the grid *17* of tube *18*, a blocking condenser *25* is interposed in the grid lead. This necessitates grounding grid *17* through a leak resistor *26*, which may also serve as a compromise terminating impedance for the 45 selector. The cathode *27* of tube *18* is grounded through impedance *28* to complete the input circuit to tube *18*. 50

Figs. 7 and 8 show the selectivity performance of the Fig. 6 selector *T*. Fig. 7 represents the 50 effect of varying only the capacitive coupling *E*, and Fig. 8 that due to variation only of the inductive coupling *M*. The selector is adjusted for single or double sideband expansion with respect to a selected frequency *f* by tuning circuits *19* and *20* by means of condensers *C* and with condenser *E* shorted, to a frequency somewhat below frequency *f*, and such that adjustment of the mutual inductance *M* for considerably over-optimum coupling will allocate the upper resonance peak at 55 frequency *f*. Upon removal of the short circuit, condenser *E* is adjusted in relation to the thus established inductive coupling to secure minimum effective coupling at frequency *f*. Due to the fact that the capacitive coupling *E* and the inductive 60 coupling *M* are effectively in series they will oppose and thereby substantially annul one another to provide this minimum coupling. 65

The frequency-response characteristic of the selector for the minimum coupling adjustment is 70 shown by curve *l* of Fig. 7. Starting from this response the selectivity is varied to provide single sideband selection by adjustment of condenser *E*. Decreasing the capacity of *E* to a properly selected limit will result in the upper sideband selec- 75

tion of curve *m*, while increasing *E* from the initial setting will shift the center of the resonance curve toward the lower frequencies while broadening the response until a desired maximum expansion 5 characteristic, such as is depicted by curve *n*, is achieved.

The resonance band is symmetrically expanded with respect to the intermediate frequency for double sideband reception by fixing the capacity 10 *E* at the value for curve *l*, Fig. 7, and varying only the mutual inductance *M*. The expansion progresses to curve *q* and thence to curve *r*, Fig. 8. The dip in curve *r*, or intermediate curves, may be 15 eliminated by terminating the selector with a resistor such as *P*, Fig. 1, of correct value. The sharp dip in curve *l* may, for this selectivity adjustment only, be minimized by shunting condenser *E* with a resistor of appropriate value.

Fig. 9 is the circuit diagram of a complete radio 20 receiving system employing a plurality of tuned expanding band selectors in accordance with the invention. The receiver, of the superheterodyne type, utilizes the tuned selectors as intertube couplings in the intermediate-frequency portion. 25 Manipulation of such a receiver entails: (1) simultaneously adjusting all tuning elements in the radio-frequency portion of the system for tuning to the reception frequency; like adjustments of the several tuned selectors to provide either 30 (2) single sideband or (3) double sideband reception of a desired selectivity; and by way of optionally included refinement, (4) inclusion at the proper point in the manipulation cycle of suitable selectivity determining resistors, such as *R* and *P* 35 of Fig. 1. The desirability is apparent of having all of these adjustments carried out by a simplified control. The mechanical construction of such a control in relation to the circuit manipulation is likewise included in the Fig. 9 showing.

In the circuit of Fig. 9, the antenna-ground circuit 40, 41 is transformer coupled to a double tuned preselector 42 comprising resonant circuits 43, 44 tuned by condensers 45, 46, respectively, and compound coupled in aiding phase relation by 45 mutual inductance 47 and capacity 48. Selector 42 applies the selected signals to the grid circuit of a stage of radio-frequency amplification, tube 49, the amplified signals from which are relayed to a modulator, tube 50, through a selector 51 comprising a transformer having a secondary tuned by 50 a variable condenser 52. The modulator cathode 53 is grounded at 54 through a biasing impedance 55 and the secondary coil of a transformer 56 the primary of which serves reactively 55 to couple the electrodes of an oscillator tube 57 for generating heterodyne oscillations of a frequency determined by the setting of a condenser 58 tapped in series with a fixed condenser 59 across a portion of the transformer primary. Heterodyne oscillations from the source, tube 57, are thus applied to the modulator tube 50 along with the signaling frequencies relayed through selector 51. A signal derived bias voltage from some point of the system may be applied to the point AVC for 60 the purpose of automatic amplification control in a conventional manner. The radio-frequency portion of the system as thus briefly described is of known construction and operation and therefore requires no detailed explanation.

In the intermediate-frequency portion of the system a tuned band selector 60, similar to that of Fig. 1, relays the modulated intermediate-frequency signals from the modulator, tube 50, to a stage of intermediate-frequency amplification, tube 61. A similar band selector 62 relays

the amplified intermediate-frequency modulated signals to a detector, tube 63, to the output of which is coupled an audio-frequency amplifier, indicated schematically by rectangle 64, and thence to a loud speaker 65.

The functions of tuning and selectivity adjustment are controlled by the mechanism shown in the lower portion of the drawings. The mechanism includes a control shaft 70 operable in two degrees of freedom. The shaft is axially displaceable between limiting positions, and rotatable by a control knob 71 affixed to the shaft terminus. The shaft is provided with a transversely projecting pin 72 adapted upon adjustment of the shaft to one limit of axial displacement to 15 mesh with the peripherally serrated collar 73. Shaft 70 is not in contact with collar 73 which is free to rotate in bearings 74 of support 75 affixed to the frame or chassis 76. Adjustment of shaft 70 to the opposite limit of axial displacement causes pin 72 to mesh the peripheral teeth of a second collar 77, likewise not contacting with shaft 70 but free to rotate in bearings 78 of supports 79. The pin 72 and collars 73 and 77 thus constitute a selective clutch mechanism whereby rotation of the control knob 71 at one limit of axial displacement rotates collar 77, whereas at the opposite limit of axial displacement knob 71 is rotatable to rotate sleeve 73.

Keyed to collar 73 is a pulley 80 carrying a belt 30 81 which drives a pulley 82 keyed to the shaft 83 of a rotary gang condenser indicated at 84. The gang condenser, the structural details of which are not shown because well known, comprises the tuning condensers 45, 46, 52 and 58 in the 35 radio-frequency portion of the system. Accordingly, adjustment of the gang condenser 84 by the mentioned manipulation of knob 71 to rotate collar 73 will simultaneously vary all the condensers mentioned to adjust the radio-frequency portion of the system to the reception frequency, as is indicated by the unitary control designation 85.

Single sideband expansion is secured by pulling knob 71 out until pin 72 engages the teeth of 45 collar 77. Keyed to collar 77 is a gear 86 which drives a gear 87 keyed to shaft 88 rotatably supported by brackets 79. Shaft 88 drives through bevelled gears 89 and 90 a shaft 91 on which are mounted the rotor elements of the coupling 50 condensers *E* in selectors 60 and 62. Therefore rotation of knob 71, when the shaft 70 is axially displaced to engage pin 72 with collar 77, adjusts the intermediate-frequency portion of the system for upper or lower sideband selection in the manner described in connection with Figs. 1 and 2. Moreover, this selectivity adjustment is accomplished without disturbing the tuning adjustment because pin 72 is now disengaged from sleeve 73.

When it is desired to tune the radio-frequency 60 portion of the system it is important that condensers *E* of selectors 60 and 62 shall be at their mid-setting. To accomplish this automatically as shaft 70 is displaced to the left to engage the tuning control 72, 73 a centering mechanism is 65 provided. For this purpose there is keyed to shaft 70 a flanged collar 92 which continuously engages a peripheral slot 93 in a sleeve member 94 axially displaceable on a shaft 95 affixed by means of nuts 96 to the frame 76. Pin 97 passing through sleeve 94 and across a flat portion of shaft 95 prevents rotation of the sleeve on the shaft. The sleeve 94 carries a tapered or bevelled guide or yoke 98 of Y configuration, the detailed construction of which is shown in plan view in 75

that rotation of the tuning control shaft 132 will operate the gang tuning condenser 130.

Double and single sideband selectivity adjustment is regulated by the expander shaft 136. 5 This shaft is axially displaceable without rotation between limiting positions, and is rotatable without axial displacement only in the one limiting position illustrated in the drawings, that is, when pushed in to maximum extent. In the position 10 illustrated in the drawings, shaft 136 is capable of rotation plus and minus 90° from a mid-position to adjust the selectivity for single sideband reception by operation of the coupling condensers E of selectors 144 and 145 in the intermediate- 15 frequency portion of a receiver, such as is illustrated in Fig. 9 and repeated in Fig. 12. The mechanical connection between the expander shaft 136 and the shaft of condensers E in gang assembly, is through the sliding coupling 146 and the shaft 147, which may be a solid or flexible shaft depending on the relative locations of shaft 136 and the rotor shaft of the gang assembly of condensers E. This mechanical coupling is indicated diagrammatically by the dashed line 148. 20 Indicator pointer 150, Fig. 17, may be carried on shaft 136 to show the amount of single sideband expansion and whether the upper or lower sideband is being received. The full "in" position of shaft 136, also adjusts the mutual inductance couplings M of selectors 144 and 145 to the correct 25 value, curve a, Fig. 2, for single sideband operation, by mechanical control of the position of the secondary coils L with respect to the associated coils L.

30 35 For double sideband expansion control shaft 136 must be rotated to the mid-position, thus correctly setting the coupling condensers E in relation to the mutual inductive couplings M to provide minimum effective coupling or maximum selectivity according to curve a, Fig. 2, after 40 which shaft 136 may be withdrawn but not rotated, to increase only the inductive couplings M for double sideband selection in the manner explained above in connection with Fig. 9. The sliding coupling 146 permits of axial translation 45 without rotation of shaft 136, thus maintaining condensers E fixed at the mid-position.

The expander control is constrained to follow the paths described, for single or double sideband 50 selection, by reason of blocks 151 affixed to bracket 152 and separated the width of pin 137. When shaft 136 is pushed in to the maximum extent, pin 137 clears blocks 151 and is thus rotatable to adjust condensers E for single sideband selection. In order to expand the resonance band for 55 double sideband selection, shaft 136 must be rotated to its mid-position to align pin 137 with the passage between blocks 151 thereby to permit axial displacement of shaft 136.

60 The lower portion of pin 137 is transversely displaceable within a slot 153 of a block 154 provided with grooves 155 for slideably supporting block 154 on spaced guides 156 paralleling shaft 136 and terminating in bracket 157. Bracket 152 is cut away as indicated at 158 to permit passage of block 154.

A shaft 159, mechanically coupled as indicated at 160 to the secondary coils L of the selectors, is slideably supported, parallel to shaft 136, by 70 brackets 161 and 162, and is affixed at one end to block 154. Axial translation is imparted to shaft 159 by axial displacement of shaft 136 transmitted through pin 137 when engaged in slot 153 of block 154. Translation of shaft 136, moving with 75 it shaft 159, can, as stated, occur only when shaft

136 is in its mid-position of rotation. This brings the upper portion of pin 137 in line with the space between blocks 151 and also in line with a corresponding slot, Fig. 14, in bracket 152 so that the pin may pass through. The initial and final positions of the secondary coils L with respect to the primary coils L are determined by the permissible travel of block 154 between brackets 157 and 161. These limiting positions are so arranged that the limited travel of block 154 will cause 10 the desired change in the mutual inductances M. The pins 156 serve additionally to prevent rotation of shaft 136 during double sideband expansion by constraining the lower portion of pin 137 to travel between them. Scale 149, on shaft 136, 15 indicates the degree of double sideband expansion.

It was suggested in the description of the Fig. 9 assembly, especially in double sideband expansion, that it might be desirable to terminate 20 selectors 144 and 145 in adjustable resistances P to smooth out the double peaks in the resonance curve due to over-optimum coupling in the expanded condition. In the system of Fig. 12 this is 25 accomplished by mechanically coupling the sliders of resistances P to shaft 159 as is indicated by the dashed lines 163.

The resistances R, suggested for use in shunt with condensers E when tuning, are cut in by 30 switches 164—167, inclusive, the operation being analogous to that described for Fig. 9.

While the adjustable selectors have been described in connection with receivers particularly of the superheterodyne type, they may also be used effectively in transmitters of the successive 35 modulation and frequency transposition type to attain control of the character of the waves finally radiated, i. e., whether they are double or single sideband with carrier and regulate the amount of sideband width. Such application is 40 important particularly in short wave signaling.

What is claimed is:

1. In a modulated carrier wave signaling system, a resonant band selector, a first means for expanding the resonance band of said selector 45 symmetrically about the carrier frequency of a modulated carrier wave to select both of its sidebands equally, and a second means for expanding said resonance band unsymmetrically with respect to said carrier to select more of one side- 50 band than of the other.

2. In a modulated carrier wave signaling system, a resonant band selector, a first means for continuously expanding the resonance band of 55 said selector symmetrically about the carrier frequency of a modulated carrier wave to select both of its sidebands equally, and a second means for continuously expanding said resonance band unsymmetrically with respect to said carrier to select more of one sideband than of the other.

3. In a modulated carrier wave signaling system, a resonant band selector, a first means for expanding the resonance band of said selector symmetrically about the carrier frequency of a modulated carrier wave to select both of the sidebands equally, and a second means for expanding said resonance band unsymmetrically in either direction with respect to said carrier to select 65 more of either sideband than of the other.

4. In a modulated carrier wave signaling system, a resonant band selector, a first means for continuously expanding the resonance band of 70 said selector symmetrically about the carrier frequency of a modulated carrier wave to select both of its sidebands equally, and a second means for 75

Fig. 10. Projecting between the tapered guides 100 and 101 of the yoke is a pin 99 affixed to the shaft 88 which controls the adjustment of condensers E in selector 60 and 62.

5 If single sideband expansion has been in use, slide 94 will have been pulled to its extreme right-hand limit and pin 99 may be in any position between guides 100, 101 of yoke 98. If now it is desired to tune in another station, knob 10 71 must be displaced furthest to the left to engage the tuning control. This forces yoke 98 to the left thus causing pin 99 to come to center between guides 100, 101 in the narrow section at the neck of the yoke thereby automatically centering condensers E.

To obtain double sideband expansion shaft 70 must be in the tuning position with clutch 72, 73 engaged and condensers E centered as described. The mechanism for effecting double 20 sideband selection includes a flanged collar 102 keyed to the shaft 70 and adapted to engage a slot 103 in a sleeve 104 which is keyed, by means of a pin 105, to a square shaft 106 and which is vertically displaceable on the shaft 106, as 25 shown in Fig. 11, to permit flange 102 to disengage the slot 103. The engagement and disengagement is effected by means of a cam 107 keyed to a shaft 108 which is operable by a knob 109. The cam is provided with a curved outer edge 30 eccentric to the axis of shaft 108, so that rotation of the shaft to displace the cam 107 between stops 109 and 110 raises or lowers sleeve 104.

Shaft 106, supported by bracket 111 affixed to the frame 76, is axially displaceable correspondingly to displace a shaft 112 in which shaft 106 is 35 terminated. Shaft 112 is mechanically connected to the movable secondary coils L of selectors 60 and 62, as indicated by the dashed lines 113, axially to displace the movable coils relative to the fixed coils L in these selectors, thereby to vary 40 the inductive coupling between coupled resonant circuits of the selectors in the manner described with reference to Fig. 1. Shaft 112 may be rigid or flexible depending on the location of this shaft in relation to the movable coils L.

45 Manipulation of the cam 107 by rotation of knob 109 to cause flange 102 to engage slot 103, places the inductive coupling adjustments M of the selectors 60 and 62 under control of the knob 71. In this way the selectivity in the intermediate-frequency portion of the system may be 50 symmetrically expanded or contracted with respect to the intermediate frequency by axial displacement of knob 71 to provide a desired selectivity for double sideband reception according to 55 the operation of Fig. 3.

To insure that double sideband expansion will 60 always be initiated from the tuning position, slide 104 is provided on its under side with a lip 114 having a transverse slot 115 at its extreme right. When the control knob 71 is in the tuning position, slot 115 will be aligned with cam 107 to permit its rotation between stops 109 and 110 thereby to engage or disengage flange 65 102 with slot 103 as desired. For all double sideband expansions, however, disengagement of flange 102 from slide 104 is prevented by lip 114 bearing against cam 107 in its actuating position.

70 It must not be possible simultaneously to adjust the inductive couplings M and the capacitive couplings E. To insure this independence of controls, the travel of slide 104 is limited by bracket 111 so that when the control knob 71 is pulled out for full double sideband expansion, pin 72 can- 75 not engage the teeth of collar 71. The proper

limits of travel for slide 104 are determined by the dimensions x and y between the ends of the slide and brackets 111, in relation to the travel of pin 72 between collars 73 and 77.

If it is found desirable to terminate the selectors 60 and 62 with resistances P to maintain uniformity of response in the transmitted band, the adjusting arms of the resistances may be mechanically coupled to shaft 112 as indicated by the dashed lines 116. In this way the terminating resistances of the selectors are varied simultaneously with and in opposite sense to the inductive couplings M and such as to assure the desired selectivity characteristic for each coupling adjustment for double sideband reception. As the 15 inductive couplings are decreased for minimum coupling, the resistances P are increased for maximum selectivity. On the other hand as the inductive couplings are increased to expand the transmitted band, resistances P are decreased at 20 a rate assuring uniformity of response in the transmitted range.

In the discussion of Figs. 1-3, inclusive, the desirability was pointed out of shunting condensers E with resistances R to increase the sensitivity 25 for the coupling adjustment providing the response of curve a, Fig. 2, but not for the expanded single or double sideband selectivity adjustments. This refinement in operation may in the system of Fig. 9 be effected by adjustment of the control knob 71. To this end the rotary arms of switches 117 and 118 are mounted on the shaft 91 of the gang condenser E as indicated by the dashed connecting lines 119. As shaft 91 is rotated by knob 71 the arms of switches 117 and 35 118 are rotated to connect resistors R across their respective condensers E, but only for their intermediate capacity settings at which condensers E in conjunction with the inductive couplings M provide the minimum total coupling between resonant circuits in accordance with curve a, Fig. 2. Since, moreover, resistances R must be disconnected for double as well as for single sideband expansions, the shunt paths through resistances R across condensers E are completed through 40 contacts of switches 120 and 121 controlled by the adjustable arms of resistances P. The contacts are so arranged, as shown, that switches 120 and 121 will be closed only when the inductive 45 couplings are adjusted by shaft 112 for maximum 50 selectivity as described.

The mechanism of Figs. 12-17, inclusive, is applicable to the circuit of Fig. 9, to effect the same tuning and selectivity adjustments as in the mechanical system shown in Fig. 9. In this embodiment, tuning to the reception frequency is accomplished by means of the gang tuning condenser 130, illustrated schematically. To this end, shaft 131 supporting the rotor elements of the gang condenser assembly, is adjusted by a tuning 55 control shaft 132 through a pulley 133, keyed to shaft 132, belt 134, and pulley 135 keyed to shaft 131. The tuning operation is subject to control by a selectivity adjusting shaft 136, and can only occur when shaft 136 is adjusted to the tuning 60 position for maximum intermediate-frequency selectivity as described below. When shaft 136 is properly adjusted for tuning, which is the position illustrated in the drawings, pin 137, extending transversely through shaft 136, pushes against 65 a raised ball section 138 of a lever 139 which pivots on pin 140, and thus moves the lever 139 away from a stop 141 against the pull of a spring 142, thereby causing idler rollers 143 to take out the slack otherwise present in the tuning belt 134; so 70 75 76

continuously expanding said resonance band unsymmetrically with respect to said carrier, thereby to select more of one sideband than of the other, said first and second means being adjustable to sharpen the tuning of said selector to said carrier frequency.

5. In a modulated carrier wave signaling system, a resonant band selector, said selector including fixed and variable reactances, a first 10 means for adjusting at least one of said variable reactances to expand the resonance band of said selector symmetrically about the carrier frequency of a modulated carrier wave to select both of its sidebands equally, and a second means for 15 adjusting at least one other of said variable reactances for expanding said resonance band unsymmetrically with respect to said carrier frequency to select more of one sideband than of the other.

20 6. In a modulated carrier wave signaling system, a resonant band selector, said selector including fixed reactance elements, an adjustable mutual inductance and an adjustable condenser, a first means for adjusting said mutual inductance 25 to expand the resonance band of said selector symmetrically about the carrier frequency of a modulated carrier wave to select both of its sidebands equally, and a second means for adjusting said condenser to expand said resonance band 30 unsymmetrically with respect to said carrier frequency to select more of one sideband than of the other.

7. In a modulated carrier wave signaling system, a band selector including a pair of reactively coupled resonant circuits, a first means for adjusting the reactive coupling of said circuits in one sense to expand the resonance band of said selector symmetrically about the carrier frequency of a modulated carrier wave thereby to 35 select both of its sidebands equally, and a second means for adjusting said reactive coupling in an opposite sense to expand said resonance band unsymmetrically with respect to said carrier frequency thereby to select more of one sideband 40 than of the other.

8. An electric wave selector of the adjustable band-pass type including a pair of resonant circuits, adjustable opposing mutual and self-reactance couplings between said circuits, a first 50 means for adjusting said mutual reactance coupling to expand the frequency band passed by said selector symmetrically about a fixed mean frequency, and a second means for adjusting said self-reactance coupling to expand the frequency band passed by said selector unsymmetrically about said fixed frequency.

9. In a modulated carrier wave signaling system, a band selector including a pair of resonant circuits, adjustable opposing mutual and self-reactance couplings between said circuits, a first 60 means for adjusting said mutual reactance coupling to expand the resonance band of said selector symmetrically about the carrier frequency of a modulated carrier wave to select both of its sidebands equally, and a second means for adjusting said self-reactance coupling to expand said resonance band unsymmetrically with respect to said carrier frequency to select more of one sideband than of the other.

70 10. In a modulated carrier wave signaling system, a band selector including a pair of resonant circuits, adjustable capacitive and inductive couplings between said circuits, a first means for adjusting said inductive coupling to expand the 75 resonance band of said selector symmetrically

about the carrier frequency of a modulated carrier wave to select both of its sidebands equally, and a second means for adjusting said capacitive coupling to expand said resonance band unsymmetrically with respect to said carrier frequency 5 to select more of one sideband than of the other.

11. In a modulated carrier wave signaling system, a resonant band selector, a first means for expanding the resonance band of said selector symmetrically about the carrier frequency of a 10 modulated carrier wave to select both of its sidebands equally, and a second means for expanding said resonance band unsymmetrically with respect to said carrier to select more of one sideband than of the other, and means for 15 preventing the operation of either of said expanding means except when the other of said expanding means is operated fully to contract said resonance band.

12. In a modulated carrier wave signaling system, a resonant band selector, means for adjusting the selective properties of said selector including a control mechanism operable in at least two degrees of freedom, means responsive to operation of said control mechanism in one 20 degree of freedom for expanding the resonance band of said selector symmetrically about the carrier frequency of a modulated carrier wave to select both of its sidebands equally, and means 25 responsive to operation of said control mechanism in another degree of freedom for expanding said resonance band unsymmetrically with respect to said carrier thereby to select more of 30 one sideband than of the other.

13. In a modulated carrier wave signaling system, a band selector comprising a pair of coupled resonant circuits, said selector including a plurality of adjustable coupling reactances, means including a control mechanism operable in at least two degrees of freedom, means responsive to 35 operation of said control mechanism in one degree of freedom for adjusting at least one of said reactances to expand the resonance band of said selector symmetrically with respect to the carrier frequency of a modulated carrier wave thereby 40 to select both of its sidebands equally, and means responsive to operation of said control mechanism in another degree of freedom for adjusting at least one other of said reactances to expand 45 said resonance band unsymmetrically with respect to said carrier thereby to select more of either of said sidebands than of the other.

14. In a modulated carrier wave signaling system, a resonant band selector, means for adjusting the selective properties of said selector including a control shaft operable in at least two degrees of freedom comprising rotation and axial displacement, means responsive to operation of said control shaft in one of said degrees of freedom for expanding the resonance band of said 50 selector symmetrically with respect to the carrier frequency of a modulated carrier wave, and means responsive to operation of said control shaft in the other of said degrees of freedom for expanding said resonance band unsymmetrically 55 with respect to said carrier frequency.

15. In a modulated carrier wave signaling system, a resonant band selector, means for adjusting the selective properties of said selector including a control shaft operable in at least two 60 degrees of freedom comprising rotation and axial displacement, means responsive to axial displacement of said control shaft for expanding the resonance band of said selector symmetrically 65 with respect to the carrier frequency of a modu- 70 75

- lated carrier wave, and means responsive to rotation of said control shaft for expanding said resonance band unsymmetrically with respect to said carrier frequency.
- 5 16. In a modulated carrier wave signaling system, a resonant band selector, means for adjusting the selective properties of said selector including a control shaft operable in at least two degrees of freedom comprising rotation and axial 10 displacement, means responsive to operation of said control shaft in one of said degrees of freedom for expanding the resonance band of said selector symmetrically with respect to the carrier frequency of a modulated carrier wave, means 15 responsive to operation of said control shaft in the other of said degrees of freedom for expanding said resonance band unsymmetrically with respect to said carrier frequency, and means including operating connections between said control shaft and said two expanding means whereby 20 selective and mutually exclusive operation of either of said expanding means is provided.
17. In a modulated carrier wave signaling system, a resonant band selector, means for adjusting the selective properties of said selector including a control shaft operable in at least two degrees of freedom comprising rotation and axial displacement, means responsive to operation of 25 said control shaft in one of said degrees of freedom for expanding the resonance band of said selector symmetrically with respect to the carrier frequency of a modulated carrier wave, means responsive to operation of said control shaft in the other of said degrees of freedom for expanding 30 said resonance band unsymmetrically with respect to said carrier frequency, and a clutch interconnecting said control shaft and that expanding means responsive to rotation thereof and disengageable upon axial displacement of said shaft 35 to operate the other of said expanding means.
18. In a modulated carrier wave signaling system, a resonant band selector, means for adjusting the selective properties of said selector including a control shaft operable in at least two degrees of freedom comprising rotation and axial 40 displacement, means responsive to operation of said control shaft in one of said degrees of freedom for expanding the resonance band of said selector symmetrically with respect to the carrier frequency of a modulated carrier wave, means responsive to operation of said control shaft in the other of said degrees of freedom for expanding 45 said resonance band unsymmetrically with respect to said carrier frequency, and means responsive to axial displacement of said control shaft for adjusting said expanding means responsive to rotation thereof to a predetermined normal setting.
- 46 19. In a modulated carrier wave signaling system, a resonant band selector, means for adjusting the selective properties of said selector including a control shaft operable in at least two degrees of freedom comprising rotation and axial 50 displacement, means responsive to operation of said control shaft in one of said degrees of freedom for expanding the resonance band of said selector symmetrically with respect to the carrier frequency of a modulated carrier wave, means responsive to operation of said control shaft in the other of said degrees of freedom for expanding 55 the resonance band of said selector unsymmetrically with respect to the carrier frequency of a modulated carrier wave, and means associated with said control shaft for preventing 60

rotation thereof when axially displaced from a predetermined position.

20. In a modulated carrier wave signaling system, a resonant band selector, means for adjusting the selective properties of said selector including a control shaft operable in at least two degrees of freedom comprising rotation and axial displacement, means responsive to operation of said control shaft in one of said degrees of freedom for expanding the resonance band of said selector symmetrically with respect to the carrier frequency of a modulated carrier wave, means responsive to operation of said control shaft in the other of said degrees of freedom for expanding the resonance band of said selector unsymmetrically with respect to the carrier frequency of a modulated carrier wave, a locking member supported from said control shaft, and guiding means for said member during axial displacement of said shaft, said guiding means being effective to restrain rotation of said shaft except when in a predetermined axial position.

21. In a modulated carrier wave signaling system, a signal-selecting and -translating circuit including a resonant band selector, means for tuning said circuit to select a modulated carrier wave, means for expanding the resonance band of said selector symmetrically about the carrier frequency of the selected modulated wave to select both of its sidebands equally, and means for expanding said resonance band unsymmetrically with respect to said carrier to select more of one sideband than of the other.

22. In a modulated carrier wave signaling system, a signal-selecting and -translating circuit including a resonant band selector, means for tuning said circuit to select a modulated carrier wave, means for expanding the resonance band of said selector symmetrically about the carrier frequency of the selected modulated wave to select both of its sidebands equally, means for expanding said resonance band unsymmetrically with respect to said carrier to select more of one sideband than of the other, and a common control mechanism for said tuning means and both of said expanding means.

23. In a modulated carrier wave signaling system, a signal-selecting and -translating circuit including a resonant band selector, means for tuning said circuit to select a modulated carrier wave, means for expanding the resonance band of said selector symmetrically about the carrier frequency of the selected modulated wave to select both of its sidebands equally, means for expanding said resonance band unsymmetrically with respect to said carrier to select more of one sideband than of the other, and a common control mechanism for said tuning means and both of said expanding means including provisions for selective and mutually exclusive operation of any thereof.

24. In a modulated carrier wave signaling system, a signal-selecting and -translating circuit including a resonant band selector, means for tuning said circuit to select a modulated carrier wave, means for expanding the resonance band of said selector symmetrically about the carrier frequency of the selected modulated wave to select both of its sidebands equally, means for expanding said resonance band unsymmetrically with respect to said carrier to select more of one sideband than of the other, and a common control mechanism for said tuning means and both of said expanding means including interlocking 75

means for preventing operation of more than one of said means simultaneously.

25. In a modulated carrier wave signaling system, a signal-selecting and -translating circuit including a resonant band selector, means for tuning said circuit to select a modulated carrier wave, means for expanding the resonance band of said selector symmetrically about the carrier frequency of the selected modulated wave to select both of its sidebands equally, means for expanding said resonance band unsymmetrically with respect to said carrier to select more of one sideband than of the other, and means for preventing operation of said tuning means except when both of said expanding means are operated fully to contract said resonance band.

26. In a modulated carrier wave signaling system, a signal-selecting and -translating circuit including a resonant band selector, means for tuning said circuit to select a modulated carrier wave, means for controlling the operation of said tuning means and for adjusting the selective properties of said selector including a control mechanism operable in at least two degrees of freedom, means responsive to operation of said control mechanism in one degree of freedom for expanding the resonance band of said selector symmetrically about the carrier frequency of a selected modulated wave to select both of its sidebands equally, means responsive to operation of said control mechanism in another degree of freedom for expanding said resonance band unsymmetrically with respect to said carrier to select more of one sideband than of the other, said control mechanism including provisions for preventing operation of said tuning means except when in a position corresponding to full contraction of said resonance band.

27. In a modulated carrier wave signaling system, a tunable selector and a tuned band selector, means for adjusting the selective properties of said band selector including a control mechanism operable in at least two degrees of freedom, means responsive to operation of said control mechanism in one degree of freedom for expanding the resonance band of said tuned selector symmetrically about the carrier frequency of a modulated carrier wave to select both of its sidebands equally, means responsive to operation of said control mechanism in another degree of freedom for expanding said resonance band unsymmetrically with respect to said carrier to select more of one sideband than of the other, operation of said control mechanism to a predetermined setting being effective to sharpen the tuning of said tuned selector to said carrier frequency, and means operative only upon operation of said control mechanism to said predetermined setting for adjusting said tunable selector throughout a frequency range.

28. In a modulated carrier wave signaling system, a plurality of tunable selectors and a plurality of tuned band selectors, means for adjusting the selective properties of said selectors including a control shaft operable in two degrees of freedom comprising rotation and axial displacement, means responsive to rotation of said control shaft for expanding the resonance bands of said tuned selectors symmetrically about the carrier frequency of a modulated carrier wave to select both of its sidebands equally, mean responsive to axial displacement of said control shaft for expanding said resonance bands unsymmetrically with respect to said carrier frequency to select more of one said sideband than of the other, operation of said control shaft to a predetermined

axial and rotational setting being effective to sharpen the tuning of said tuned selectors to said carrier frequency, and means operative only upon adjustment of said control shaft to said predetermined setting for adjusting said tunable selectors throughout a frequency range.

29. In a modulated carrier wave signaling system, a tunable selector and a tuned band selector, means for adjusting the selective properties of said band selector including a rotatable control shaft axially displaceable between limits, means responsive to displacement of said shaft to one of said limits for sharply tuning said tuned selector to the carrier frequency of a modulated carrier wave, and responsive to axial displacement of said shaft from said limit for expanding the resonance band of said tuned selector symmetrically about said carrier frequency for selecting both said bands equally, means responsive to rotation of said shaft at said limit for adjusting said tunable selector throughout a frequency range, and means responsive to rotation of said shaft at its opposite limit of axial displacement for expanding the resonance band of said tuned selector unsymmetrically with respect to said carrier to select more of one sideband than of the other.

30. In a modulated carrier wave signaling system, a tunable selector and a tuned band selector, means for adjusting the selective properties of said band selector including a rotatable control shaft axially displaceable between limits, means responsive to the displacement of said shaft to a certain angular setting at one of said limits for sharply tuning said tuned selectors to the carrier frequency of a modulated carrier wave and responsive to rotation of said shaft at said limit for expanding the resonance band of said tuned selector unsymmetrically with respect to said carrier to select more of one sideband than of the other, means operative only for said setting of said shaft for adjusting said tunable selector throughout a frequency range, and means responsive to axial displacement of said shaft from said certain setting for expanding the resonance band of said tuned selector symmetrically about the carrier frequency to select both sidebands equally.

31. In a superheterodyne modulated carrier wave receiving system, a plurality of tunable reception frequency selectors and tuned intermediate-frequency band selectors, means for adjusting the selective properties of said selectors including a control mechanism operable in at least two degrees of freedom, means responsive to operation of said control mechanism in one degree of freedom for expanding the resonance bands of said tuned selectors symmetrically about the intermediate frequency to select both sidebands of a modulated carrier wave equally, means responsive to operation of said control mechanism in another degree of freedom for expanding said resonance bands unsymmetrically with respect to said intermediate frequency to select more of one sideband than of the other, operation of said control mechanism to a predetermined setting being effective to sharpen the tuning of said tuned selectors to said intermediate frequency, and means operative only upon adjustment of said control mechanism to said predetermined setting for adjusting said tunable selectors throughout a frequency range.

32. In a modulated carrier wave signaling system, a resonant band selector, an adjustable resistance termination for said selector, a first

means for adjusting said resistance and for expanding the resonance band of said selector symmetrically about the carrier frequency of a modulated carrier wave to select both of its sidebands equally while maintaining transmission reasonably uniform within said band, and a second means for expanding said resonance band unsymmetrically with respect to said carrier frequency to select more of one sideband than of the other.

33. In a modulated carrier wave signaling system, a band selector including a pair of resonant circuits, adjustable capacitive and inductive couplings between said circuits, an adjustable resistance termination for said selector, a first means for adjusting said resistance and said inductive coupling to expand the resonance band of said selector symmetrically about the carrier frequency of a modulated carrier wave thereby to select both of its sidebands equally while maintaining transmission reasonably uniform within said band, a second means for adjusting said capacitive coupling to expand said resonance band unsymmetrically with respect to said carrier frequency thereby to select more of one sideband than of the other, said first and second means being adjustable to sharpen the tuning of said selector to said carrier frequency.

34. In a modulated carrier wave signaling system, a band selector including a pair of resonant circuits, adjustable capacitive and inductive couplings between said circuits, a resistor, a first means for adjusting said inductive coupling to expand the resonance band of said selector symmetrically about the carrier frequency of a modulated carrier wave to select both of its sidebands equally, a second means for adjusting said capacitive coupling to expand said resonance band unsymmetrically with respect to said carrier frequency to select more of one sideband than of the other, said first and second means being adjustable to predetermined settings to sharpen the tuning of said selector to said carrier frequency, and means for connecting said resistor in shunt to said capacitive coupling only when both of said means are adjusted to said settings.

35. In a modulated carrier wave signaling system, a band selector including a pair of resonant circuits, said circuits being reactively coupled, and a reactance element coupling said circuits in opposition to said first coupling, said reactance element being self-reactance adjustable between limits greater and less than that value whose coupling is equal and opposite to said first coupling to adjust the width of the band passed by said selector to a minimum about a frequency corresponding to the desired carrier wave and to expand the same unsymmetrically about said carrier frequency to select more of either sideband than the other.

36. In a modulated carrier wave signaling system, a band selector including a pair of resonant circuits, a first reactance element coupling said pair of circuits in excess of optimum coupling, a second reactance element coupling said pair of circuits in opposition to said first coupling, said second reactance element being self-reactance adjustable between limits greater and less than that value whose coupling is equal and opposite to said first coupling to adjust the width of the band passed by said selector to a minimum about a frequency corresponding to the desired carrier wave and to expand the same unsymmetrically about said carrier frequency to select more of either sideband than the other.

means for adjusting said resistance and for expanding the resonance band of said selector symmetrically about the carrier frequency to select more of either sideband than the other.

37. In a modulated carrier wave signaling system, a band selector including a pair of resonant circuits, said circuits being reactively coupled, and means for adjusting the width of the resonance band of said selector and simultaneously adjusting the mean frequency thereof on either side of said carrier frequency comprising a reactance element coupling said circuits in opposition to said first coupling, said reactance element being self-reactance adjustable between limits greater and less than that value whose coupling is equal and opposite to said first coupling.

38. In a modulated carrier wave signaling system, a band selector including a pair of resonant circuits, said circuits being reactively coupled in excess of optimum, and a reactance element coupling said circuits in opposition to said first coupling, said reactance element being an adjustable self reactance having a maximum reactance the coupling of which is of the order of twice said first coupling to adjust the width of the band passed by said selector to a minimum about a frequency corresponding to the desired carrier wave, and to expand the same unsymmetrically about said carrier frequency to select more of either sideband than of the other.

39. In a modulated carrier wave signaling system, a band selector including a pair of resonant circuits, an inductive coupling between said circuits, and an adjustable condenser coupling said circuits in opposition to said inductive coupling, said condenser being adjustable between limits greater and less than that value whose coupling is equal and opposite to said inductive coupling to adjust the width of the band passed by said selector to a minimum about a frequency corresponding to the desired carrier wave and to expand the same unsymmetrically about said carrier frequency to select more of either sideband than of the other.

40. In a modulated carrier wave signaling system, a band selector including a pair of resonant circuits, a shunt inductive coupling between said circuits of over-optimum value, a series capacitive coupling between said circuits acting in opposition to said inductive coupling, said capacitive coupling comprising an adjustable condenser having a maximum capacitance corresponding to a coupling of the order of twice that of said inductive coupling to adjust the width of the band passed by said selector to a minimum about a frequency corresponding to the desired carrier wave and to expand the same unsymmetrically about said carrier frequency to select more of either sideband than of the other.

41. In a modulated carrier wave signaling system, a band selector including a pair of resonant circuits, a series inductive coupling between said circuits, a shunt capacitive coupling between said circuits, said capacitive coupling comprising a condenser adjustable between limits greater and less than that value whose coupling is equal and opposite to said inductive coupling to adjust the width of the band passed by said selector to a minimum about a frequency corresponding to the desired carrier wave and to expand the same unsymmetrically about said carrier frequency to select more of either sideband than of the other.

42. In a modulated carrier wave signaling system, a band selector including a pair of resonant circuits, a reactive coupling between said circuits

2,054,412

adjustable from a predetermined value to adjust the width of the resonance band of said selector symmetrically about a frequency corresponding to the desired carrier wave, and a reactance element coupling said circuits, said reactance element being a self-reactance adjustable between limits greater than and less than that value whose coupling is equal and opposite to said

first coupling to adjust the width of said band to a minimum about a frequency corresponding to the desired carrier wave and to expand the same unsymmetrically about said carrier frequency to select more of either sideband than of the other.

JOHN F. FARRINGTON.
